UNITED STATES PATENT OFFICE.

ELIJAH HARVEY WHEELER, OF CORPUS CHRISTI, TEXAS.

LOCK-STITCH RIPPER.

SPECIFICATION forming part of Letters Patent No. 296,492, dated April 8, 1884.

Application filed October 17, 1883. (No model.)

To all whom it may concern:

Be it known that I, ELIJAH H. WHEELER, a citizen of the United States, residing at Corpus Christi, in the county of Nueces and State 5 of Texas, have invented a new and useful Improvement in Lock-Stitch Rippers, of which the following is a specification, reference being had to the accompanying drawings.

This invention relates to an improved combination tool or implement designed to be used in connection with sewing-machines, and combining in a convenient form several instruments which operators on sewing-machines should always have ready at hand.

15 The invention consists, specifically, of a handle having several folding blades, like an ordinary pocket-knife, one of which blades is a lock-stitch ripper, another a hook for holding material in position to be sewed, and the third 20 an ordinary knife-blade.

The construction and arrangement of the several parts will be hereinafter fully described, and particularly pointed out in the claim.

In the drawings hereto annexed, Figure 1 25 is a perspective view of the device with the several blades open or unfolded. Fig. 2 is a side view on an enlarged scale of the lock-stitch ripper, and Fig. 3 is a side view on an enlarged scale of the holding-hook.

30 The same letters refer to the same parts in all the figures.

A in the drawings designates the handle, which is that of an ordinary pocket-knife, and which is provided with blades B, C, and 35 D. One of the said blades, B, is forked, as at E, the inner edges of the said fork being ground sharp, so as to be capable of cutting the thread, as is the purpose of the said blade. One of the prongs G of the forked blade B is

rounded, as at H, the object being to utilize 40 the said blade for picking the threads out of the fabric after being cut or ripped. The second blade, C, is formed or provided with a sharp-pointed hook, K, which may be used as a crochet-hook, but the principal use of which 45 is to assist the operator in pushing or pulling the material to be sewed under the presser-foot of the machine, especially when attachments such as the hemmer or gatherer are used. The fingers of the operator, when such attachments are used, are too clumsy to pull or push the material into place, and hence the hook provided in my improved implement will be found useful. The blade D of the device is 50 an ordinary knife-blade, the uses of which are 55 manifest.

This invention provides in a simple and accessible form several implements which are important and useful for operators on sewing-machines. It is inexpensive, convenient, and 60 durable.

I claim as my invention and desire to secure by Letters Patent of the United States—

As an improvement in rippers, the combination, with the knife-handle A, of the lock-stitch ripper comprising the blade B, bifurcated or slotted centrally at one end, the adjoining edges of which are beveled inwardly and ground sharp, one prong of said blade being rounded, as and for the purpose set forth. 70

In testimony that I claim the foregoing as my own I have hereto affixed my signature in presence of two witnesses.

ELIJAH HARVEY WHEELER.
